SUCTION DRUM PRESS

Lloyd Hornbostel, Beloit, Wis., assignor to Beloit
Iron Works, Beloit, Wis., a corporation of Wisconsin

Application March 11, 1944, Serial No. 525,979

5 Claims. (Cl. 32—53)

1

This invention relates to suction drum presses for paper making machines wherein wet, fragile paper webs are pressed between felts in a vertical nip draining by gravity away from the felt and web and wherein both faces of the nip are subjected to suction so that water from the web passes laterally outward from both faces of the web through both covering felts.

The invention deals specifically with cylinder type paper making machines having pick-up felts with wet, soggy newly formed paper webs thereon directed under a suction drum and wrapped around the periphery of the drum through a vertical nip defined by the drum and a cooperating suction roll. A top felt is also preferably directed around the drum to cover the web on the pick-up felt in advance of the nip. In one embodiment of the invention the pick-up felt and top felt follow over the top of the suction drum to carry the paper web back over the cylinder mold. In this embodiment the suction drum is preferably equipped with a light suction area following the suction nip area to hold the web and felt on the drum.

In another embodiment of the invention the pick-up felt of the cylinder type paper making machine conveys the web under the suction drum and the web is covered with a top felt within a suction area of the drum. A cooperating suction press roll having a suction area positioned at the nip between the drums and extending past the nip transfers both felt and web to the cooperating roll. This roll has a second suction press nip receiving the felt and web therein.

In both embodiments of the invention, gravity drainage of water from a vertical nip is away from the felt and web, so that squeezed out water from the self-draining nip cannot rewet the felt or web. This is important if one or both rolls is a plain roll.

While the invention will hereinafter be specifically described in connection with a cylinder type paper making machine, it will be understood that the suction drum presses of this invention are adapted for usage in other types of machines.

It is, then, an object of the invention to provide a suction drum press which subjects a paper web simultaneously to the action of pressure and oppositely pulling suction which draws moisture from both faces of the web being pressed.

A further object of the invention is to provide a suction press for paper making machines wherein top and bottom covering felts for a paper web are simultaneously subjected to pressure and suction for drawing water through both faces of the web.

A still further object of the invention is to provide a cylinder type paper making machine wherein the pick-up felt is trained around a suction drum, subjected to suction on the lower portion

of the drum, subjected to pressure between the upper and lower portions of the drum, and subjected to light suction on the upper portion of the drum.

5 A further object of the invention is to provide a suction drum press for cylinder type paper making machines receiving the pick-up felt from the last cylinder mold and providing a self-draining suction nip for the pick-up felt with the paper web thereon.

A still further object of the invention is to provide a suction drum press with a vertical nip which receives a paper web covered by top and bottom felts in an upward direction around one of the rolls defining the nip so that water squeezed out of the nip will drain by gravity from the felts and web.

A still further object of the invention is to provide a suction press for paper making machines which has suction areas in cooperating suction rolls acting on the same pressure nip.

A still further object of the invention is to provide a cylinder type paper making machine with a suction press assembly receiving the pick-up felt of the machine and subjecting the same to suction in advance of a pressure nip and increasing the amount of suction at the pressure nip while simultaneously pressing the felt.

Other and further objects of the invention will be apparent to those skilled in the art from the following detailed description of the annexed sheets of drawings which, by way of preferred examples, illustrate two embodiments of the invention.

35 On the drawings:

Figure 1 is a side elevational diagrammatic view, with parts in vertical cross section, of a cylinder type paper making machine equipped with one form of suction drum press according to this invention.

Figure 2 is a view similar to Figure 1 but illustrating a cylinder type paper making machine equipped with another embodiment of a suction drum press according to this invention.

45 As shown on the drawings:

In Figure 1 the reference numeral 10 designates a vat of a cylinder type paper making machine rotatably carrying a cylinder mold 11 partly immersed in stock in the vat and partly extending above the open top of the vat. A pick-up felt 12 is directed over the top of the cylinder mold 11 and a couch roll 13 within the loop of the pick-up felt 12 acts on the felt to couch off a paper web W from the cylinder mold. The pick-up felt 12 supports the web W on the under face thereof.

While only one vat, one cylinder mold, and one couch roll are disclosed in the drawings, it will be understood that a plurality of such vats, molds, and rolls can be used in advance of the illus-

trated assembly, and the pick-up felt 12 can be directed over the tops of each of the cylinder molds to build up a laminated web W on the under face thereof.

In accordance with this invention a suction drum press assembly 14 is mounted immediately adjacent the vat 10, to receive the pick-up felt and web from the last cylinder mold of the cylinder machine.

The suction drum press assembly 14 includes a suitable frame 15 supporting suction rolls or drums 16 and 17. The drum 16 includes a rotatably mounted perforated cylinder 18, a stationary suction gland or suction box 19 within the cylinder 18, a suction trunnion pipe 20 for draining the suction box 19, and packing strips 21, 22 and 23 on the suction box 19 cooperating to provide localized suction areas A and B of appreciable width on the cylinder or shell 18. As shown, packing strip 21 is on the under side of the suction box 19 and the packing strip 22 is at about the horizontal center of the shell. A wide suction area A is provided between the packing strips 21 and 22 and, since this area extends to the under side of the suction box, a portion of the box 19a continues upwardly from the strip 21 to retain water in the suction box. This leaves a reduced opening 19b in the suction box for connecting the suction area A with the interior of the box. The opening 19b, however, is unobstructed.

The third packing strip 23 is provided on the box 19 at the top thereof and cooperates with the strip 22 to define a wide suction area B extending from the horizontal center line of the shell to the top portion thereof. The suction gland or suction box only has a reduced opening 19c connecting the suction area B with the interior thereof and a butterfly-type valve 24 is provided in this opening 19c to adjust the size of the opening for varying the suction in the suction area B as compared with the suction in the suction area A. This valve 24 is usually set so that the suction in area B is lower than the suction in area A.

The roll 17 is rotatably mounted on levers such as 25 pivoted at their lower ends on the frame 15 and having rods 26 projecting from their upper ends to jacks such as 27 which act on arms such as 28 of the drum assembly. The jacks 27 can be regulated to pull the levers for moving the roll 17 into pressure relation with the roll 16. The roll 17 includes a perforated shell or cylinder 29 which is rotatable around a stationary suction gland or box 30. The suction gland or box has spaced opposed packing strips 31 and 32 extending therefrom into sealing relation with the cylinder 29 to define therebetween a restricted suction area C at about the horizontal center plane of the shell 29.

The pick-up felt 12 is directed around the under side of the shell 18 in advance of the suction area A so as to cover this suction area. The web W on the pick-up felt 12, of course, is subjected to the suction in the suction area A, and water in the web is sucked through the felt 12. A top felt 33 is directed by a roll 34 to meet with and cover the web W on the felt 12 on the under side of the shell 18 intermediate the ends of the suction area A.

The shells 18 and 29 cooperate to define an upward passage vertical nip N from which water can drain by gravity as illustrated into a trough 35 without contacting either of the felts or the

web therebetween. Such drainage occurs if the roll 17 is a plain roll and such a plain roll may be used if desired.

As shown, the packing strips 22 and 32 in the cooperating rolls 16 and 17 are substantially in horizontal alignment so that the suction area A and the suction area C terminate at the same point in the nip. The nip is thus subjected to suction from the area A drawing water from the web W through the felt 12 and suction from the area C drawing water from the web W through the felt 33. The water in the web therefore passes through both faces thereof into both felts, and through these felts into opposed suction chambers. There is no pile up of water in advance of the nip since the nip opens downwardly and is self-draining.

The two felts with the web therebetween, after passing through the nip N, pass around the top of the cylinder 18 over the suction area B where they are held tightly on the cylinder by a light suction existing in the area B.

After passing over the top packing strip 23 the vacuum in the holes of the cylinder 18 is broken and any water released from these holes is caught in a collecting trough 36 so that it cannot drain down and rewet the felt 12. The web W passes between the two felts 12 and 33 as indicated and guide rolls such as G then serve to direct the felts away from the web and back to the cylinder mold 11 and suction drum 16. A wringer roll 37 can be provided to cooperate with the roll 34 for squeezing the felt 33 before it recontacts the web W. Likewise the suction box 38 can be provided to dry the felt.

In the embodiment of Figure 1, the suction drum 16 receives both felts and web around the top thereof and the felts convey the web over the top of the cylinder mold to a drier section (not shown). In this assembly the pick-up felt, when traveling over the cylinder mold to pick up the web therefrom, is traveling away from the drier section.

In the embodiment shown in Figure 2 of the drawings a cylinder type paper making machine of the type wherein the pick-up felt passing over the cylinder mold is traveling toward the drier section is equipped with a suction drum press of this invention.

In Figure 2 parts identical with parts described in connection with Figure 1 have been marked with the same reference numerals.

The suction drum press 40 of Figure 2 includes the same drum 16 as the press 14 of Figure 1, but the cooperating roll or drum 41 is different than the roll 17 of Figure 1. As shown in Figure 2 the drum 41 includes a rotating perforated cylinder or shell 42 containing a stationary suction gland or box 43 therein. The box 43 has packing strips 44, 45, 46 and 47 projecting therefrom to define three suction areas D, E and F on the cylinder 42. The suction area D is at the nip N of the assembly and is in direct communication with the interior of the suction box 43. The suction area E between the strips 45 and 46 is a relatively wide area extending between the areas D and F and having restricted communication through an opening 43a with the interior of the suction box. A butterfly valve 48 is provided in this opening 43a to control the effective size of the opening for regulating the degree of vacuum in the area E. The suction area F between the packing strips 46 and 47 is in direct communication with the interior of the suction gland and is at the top of the cylinder 42. A top press roll 49 is rotatably mounted on top

of the cylinder 42 and cooperates to define therewith a horizontal nip N'.

The packing strip 22 of the suction drum 16 is positioned at a level between the levels of the strips 44 and 45 of the roll 41 so that the suction area A overlaps the suction area D but terminates in advance of the suction area D.

The pick-up felt 12 with the web W thereon from the cylinder mold 11 is brought onto the shell 18 of the drum 16 as defined in connection with Figure 1, and the top felt 33 covers the web on the shell 18 intermediate ends of the suction area A and in advance of the nip N. The web W between the felts 33 and 12 is brought into this vertical nip N where any free water can drain by gravity into the trough 35 and where the web is subjected to suction applied through both felts from the suction area A and from the suction area D. The suction area D continues beyond the nip end and aids in the transfer of the felts and web to the cylinder or shell 42 of the roll 41. In this arrangement the valve 24 closes the opening 19c in the suction box 19 of the drum 16 since the suction area B is uncovered and should not be exposed to the interior of the suction box. The web between the felts travels on the shell 42 over the suction area E which holds the felts and web on the shell and which prevents water in the holes of the shell from being discharged outwardly back through the felt 33 into the web. The web and felts then pass over the suction area F and through the horizontal nip N'. Any water discharged from the holes in the shell 42 after the same pass beyond the suction area F will be collected in the trough 35.

The pick-up felt 12 is separated from the web W and trained around the top press roll 48 as shown. The felt 33 then conveys the web W on the top thereof to the drier section and the felt is returned as shown.

If desired, and as an alternative arrangement, the felts can be separated after passage through the vertical nip N and the pick-up felt 12 returned around the suction drum 16 as shown in dotted lines. In this arrangement the valve 24 will of course be opened to hold the water in the holes of the shell 18 until the felt leaves the shell. The top felt 33 then goes up on around the suction roll 41 and is subjected to pressure in the nip N'. When the felts are divided in the nip N, it is highly desirable that the suction area D extend slightly above the nip to make sure that the sheet or web W sticks to the top felt 33 and goes on around the roll 41.

From the above descriptions it will be understood that the invention greatly simplifies water removal problems on cylinder type paper making machines and provides suction drum presses which efficiently extract the water from wet, soggy webs without in any way damaging the webs and without permitting the webs to be rewet.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a cylinder type paper making machine including a looped pick-up felt for receiving a paper web from the cylinder mold of the machine on the under face thereof and a looped covering felt for covering said web on said pick-up felt, a suction roll within the loop of each felt,

said suction rolls cooperating to define an upward passage nip, suction boxes in each suction roll defining directly opposed suction areas on the roll on each lateral side of the nip, and said suction roll within the loop of the pick-up felt receiving the pick-up felt and covering felt thereon in advance of the nip and having an additional suction area extending around the underside thereof in advance of said nip acting on both felts before they reach the pressure portion of the nip, said additional suction area extending beyond the initial point of common lapping of said felts on such roll, thereby removing excess liquid from said pick-up felt and web prior to contact of said covering felt therewith.

2. A suction press comprising first and second horizontally aligned rolls defining an upward passage vertical nip, a top roll cooperating with said second roll to define a horizontal nip, a pick-up felt lapping the top and bottom of the first roll and extending around the nip-defining side thereof, a cover felt lapping the underside of the first roll and the top portion of the second roll to pass through both the vertical and the horizontal nip out of the path of drainage from the vertical nip, said first roll having a high vacuum area extending from the underside thereof into the vertical nip and a low vacuum area extending from said nip around the top part of the roll to hold the water in the holes, and said second roll having high vacuum areas at both nips together with an intermediate low vacuum area holding the water in the holes of the roll as it passes between the nips.

3. A suction drum press comprising first and second horizontally aligned rolls defining a vertical upward passage nip, a wet web carrying felt trained around the nip side of the first roll contacting said roll substantially from the bottom to the top thereof, said first roll having a suction box therein defining two adjacent suction areas with the first area extending from the underside of the roll to the nip and the second area extending from the nip to the top of the roll, said first area communicating with the interior of the suction box only adjacent the nip for retention of fluids in the bottom of the box, and a valve connecting the second area with the interior of said box to control the degree of vacuum in the second area, a cover felt, means for training said cover felt into contact with the web and then through the nip, the initial contact between said cover felt and the web being located adjacent an intermediate portion of said first suction area, thereby removing excess liquid from the web prior to contact of said cover felt therewith.

4. In combination, a suction press comprising cooperating suction rolls arranged for rotation to define an upward passage nip therebetween, a suction box in one roll defining a first suction area at said nip, a suction box in the other roll defining a second suction area extending from near the bottom of said other roll upwardly to said nip, means guiding a pickup felt with a wet paper web on its underside across the face of said second suction area, means for guiding a covering felt into contact with the web below and laterally of said nip, said covering felt initially contacting said web adjacent an intermediate portion of said second suction area, and means below the nip for collecting liquid which may be squeezed downwardly at the nip in excess of the rate at which said liquid may be drawn into the adjoining suction areas.

5. In a paper making machine including a

looped pick-up felt for carrying a wet web and a looped cover felt to cover the web on the pick-up felt, a roll within the loop of each felt, said rolls cooperating to define an upward passage pressure nip, thereby providing free gravitational drainage of liquid pressed from said nip, a suction box in said roll within the loop of the pick-up felt, said suction box having a suction area adjacent said upward passage pressure nip, means for guiding both felts with the web therebetween into said nip in contact with said suction roll, thereby positioning both felts out of the path of liquid draining from said nip, said suction area extending in advance of said nip beyond the initial point of common lapping of said felts on such roll, thereby removing excess liquid from said pick-up felt and web prior to contact of said cover felt therewith.
